UNITED STATES PATENT OFFICE.

JOHN C. METZGER, OF CHICAGO, ILLINOIS.

AIR-VALVE FOR CARBURETERS.

1,105,090.

Specification of Letters Patent. Patented July 28, 1914.

Application filed June 15, 1912. Serial No. 703,809.

To all whom it may concern:

Be it known that I, JOHN C. METZGER, a citizen of the United States, residing at Chicago, in the county of Cook and State of Illinois, have invented certain new and useful Improvements in Air-Valves for Carbureters, of which the following, taken in connection with the drawing, is a description.

My invention has for its object the production of a carbureter valve of a design known as the sleeve type. This valve is adapted for use on automobiles, motor cycles, motor boats, stationary gas engines, and the like, where air and oil are mixed in a chamber in the several different ways in which it is now done.

By the use of my apparatus the amount of air admitted to the mixing chamber may be regulated by an attachment having connection with a carbureter, and which is connected by means of a flexible shaft to mechanism for operating the same which is secured to the steering rod, in the event the device is used on an automobile, or at any other convenient place if used on different kinds of machines.

A further object of my invention is to provide a regulator which will not only accomplish the advantages above set forth, but at the same time effect a very material saving in the amount of gasoline required for the operation of the machine.

In the accompanying drawings I have illustrated what I now consider the preferred form of my invention, although it is obvious that other methods for carrying out the operation thereof may be employed without departing from the spirit of my invention and in these drawings—

Figure 1 is a side elevation of a carbureter with my valve secured thereto, together with the operating mechanism secured to the steering rod of an automobile, the flexible shaft being broken; Fig. 2 is a longitudinal sectional view of the valve; Fig. 3 is a transverse sectional view taken on line 3—3 of Fig. 2; Fig. 4 is a plan view of the operating attachment secured to the steering rod of an automobile.

Referring to the drawing A represents the carbureting chamber of the carbureter, which may be of any well known type, and which will therefore not be further explained. Entering the carbureting chamber preferably at the bottom thereof is a coupling B to which is secured the barrel B' of

the valve which is cylindrical in form and which is provided with apertures b extending helically around the same. A hexagon nut b' is formed integrally with the barrel, by means of which it may be readily turned into position. Sliding in this barrel is a sleeve C which is provided with a transverse partition c, through which partition extends the wire C', which is secured in fixed position by means of the set screw c'. One end of the barrel B' is closed by means of the plug D into which is secured the flexible tubular casing D' which is fixed in position by the screw D².

The wire C' extends through the flexible tubular casing D' and is connected with the operating lever E, which is secured to the bracket E' at e. The bracket E' is rigidly secured in this instance to the steering rod F of an automobile. This bracket E' is provided with an arm e² which is curved on the arc of a circle, as shown in Fig. 1. One side of this arm is provided with a knurled or otherwise roughened surface to afford friction as the lever is moved across the same.

In operation the gasoline or other material being used, is fed through the pipe G to the carbureting chamber A from whence the mixture makes its exit to the engine through the opening G'. The operation of the valve is effected by the attendant moving the lever E across the roughened surface e², which action through the wire C', extending through the flexible tubular casing, moves the sleeve C in the barrel to open or close some of the holes b thereby increasing or decreasing the amount of air passing therethrough to the carbureting chamber A. The sleeve C is made to fit closely in the barrel B' and by the helically arranged openings b the amount of air allowed to pass therethrough may be regulated to a nicety. By carburizing in the chamber as heretofore explained with my improved valve I am able to run an automobile four to five miles farther with each gallon of gasoline used than can be done without the use of this valve.

I claim:

1. A carbureter valve comprising in combination a barrel having a plurality of openings helically arranged in the wall thereof, a plug in one end of said barrel, a coupling engaging the opposite end thereof and adapted to communicate with the interior of

the carbureter, a sleeve slidable in said barrel, said sleeve having a transverse partition mediate of the length thereof, a flexible tubular casing secured in the aforesaid plug, a wire extending through said tubular casing and engaging the sleeve partition, and a lever operating through said wire to move said sleeve and regulate the amount of air admitted through the apertures in the barrel, substantially as described.

2. A carbureter valve, comprising in combination a barrel having a plurality of openings helically arranged in the wall thereof, a plug in one end of said barrel, a sleeve slid-
15 able in said barrel, said sleeve having a

transverse partition mediate of the length thereof, operating mechanism, a tubular casing connecting the aforesaid plug and the operating mechanism, a wire secured to the sleeve partition and extending through said plug and casing to the operating mechanism whereby the sleeve may be moved in the barrel, substantially as described.

In testimony whereof I have signed this specification in the presence of two subscr-
25 ing witnesses.

JOHN C. METZGER.
